ABSTRACT: This is a telescoping switch having a spring in the plunger assembly which requires greater force for compression than the spring in the contact assembly with the plunger assembly directly associated with the contact assembly. The switch includes a plunger assembly in which a first plunger is telescopically associated within a second plunger and the second plunger is telescopically associated within a divider.

TELESCOPING SWITCH

BACKGROUND OF THE INVENTION

1. Field of the Invention

The type of switch described hereinafter is used in the appliance industry particularly in household refrigerators and other appliances. This switch may also be used in any location in which a door switch is utilized, such as automobiles. The switch must be one that is self-adjusting. In other words, it should provide for overtravel caused by variations in cabinet or door construction. In the refrigerator field, the switch is usually mounted on the breaker strip in the cabinet and opening and closing of the door in relation to the cabinet physically activates the switch. A switch in this position and for this usage should also be constructed to prevent someone washing the switch from electrical hazards.

2. Description of the Prior Art

The patent to Janos, U.S. Pat. No. 2,658,968 describes a spring 12 in a switch plunger which acts as a lost motion device on movement of the bellows 2.

The patent to Loesch, U.S. Pat. No. 3,172,981 described a switch spring 25 which acts as a lost motion design after the plunger 28 is free to travel without causing movement of the contact 40.

Neither the Janos or the Loesch patents utilize a telescoping element within which the spring moves and in which the plunger also moves.

The patents to Basso, U.S. Pat. No. 2,921,155, to Furman, U.S. Pat. No. 3,249,727, and to Basso, U.S. Pat. No. 3,393,281 describe door switches which have a telescoping element in operation with the plunger in which the telescoping element is moved inwardly on a one shot installation operation to provide a self-adjusting feature. In the initial activation of this switch, the plunger is depressed by the door until its free end is in registry with the free end of the telescoping element upon the closing of the door, the plunger in the telescoping element will be depressed inwardly thereby being fixedly positioned within the door. Upon the opening of the door, the plunger will be returned to its initial position with the telescoping element fixedly positioned by friction within the switch housing.

None of the telescoping elements of the patents mentioned hereinabove are adequate to move back from the telescoping position.

SUMMARY OF THE INVENTION

The switch includes a control carrying element which floats between a plunger spring and a contact spring. The outside end of the plunger spring butts against the plunger which is depressed by a door or the like. The plunger spring described affords a lost motion on the plunger which is made in two telescoping parts so that the spring maybe compressed the full length of the two part structure while the telescoping plunger occupies only about two-thirds of the space in the housing that would be required by a nontelescoping plunger.

An object of the present invention is to provide an appliance switch assembly which is readily installed.

Another object of this invention is to provide a switch having a two part plunger the parts of which are telescopically associated.

A still further object of the invention is to provide a switch which is water resistant while providing for overtravel of the plunger.

DESCRIPTION OF THE DRAWINGS

FIG. 1 is a perspective of the switch.

FIG. 2 is a section of the switch shown in FIG. 1.

FIG. 3 is the outside section showing a different view of the switch in FIG. 2.

FIG. 4 is a section taken on line 4—4 of FIG. 2.

DESCRIPTION OF THE PREFERRED EMBODIMENT

The switch 10 comprises an inner plunger 12, an outer plunger 14, a plunger spring 16, a divider 18, a body 20, a seal element 22, a case 24, a pair of fixed terminals 26, a movable contact 28, and a contact spring 30.

The plunger assembly includes the outer and inner plungers 14 and 12, plunger spring 16 and the divider 18. The inner plunger 12 comprising a tubular body closed at one end and open at the other. An annular flange 32 extends radially outwardly adjacent the open end. The outer plunger 14 is open at both ends, and lipped over at one end to provide an internal circumferential shoulder 34 and has its opposite end thickened on the external surface to provide a flange 36. The divider 18 comprises a circular base portion 38 having a rod portion 40 extending axially and centrally from one side and a cylindrical post portion 42 extending axially and centrally from the other side. A circular wall 44 extends upwardly from the edge of the base portion 38 in spaced relation to the rod portion 40. The wall 44 includes a forward edge. Four rectangular slots are formed through the base portion 38 up into the wall 44. Each of the rectangular slots terminates near the forward edge of the wall 44 and has a forward wall with a tongue 46 extending therefrom. The tongue 46 is angled inwardly toward the rod portion 40. Four narrow slots extend into the wall 44 toward the base portion 38 from the forward edge. Both the narrow slots and rectangular slots are equally spaced around the circumference of the wall 44, and are in staggered relation to each other.

The body 20 includes a cylindrical plunger holder or upper portion 48 having a top surface and an annular flange 50 extending radially from an end and forming a right angle with the plunger holder 48. An aperture 52 is formed axially and centrally through the plunger holder 48. A cavity is formed within the plunger holder 48 of greater diameter than the aperture 52 and into which the aperture 52 opens. Arced guides extend downwardly from the plunger holder 48 adjacent the cavity and in opposed relation with each other. An integral leg 54 extends from each side of the plunger holder 48 in opposed relation to each other and spaced from each other. Each of the legs 54 has transversely arced inner and outer surfaces and each of the inner surfaces has a vertical slot 56 formed therein. An integral ring portion 58 joins the legs 54 and provides a plane which is in spaced, parallel relation to the annular flange 50. Two arms 60 extend from the ring portion 58 toward the flange 50. The arms 60 are in spaced opposed relation to each other with a leg 54 between them on each side as shown in FIG. 1, and each leg 54 has a free terminal end as well as a knuckle. The vertical slot 56 is continued through the ring portion 58. Each of the legs 54 is continued beyond the ring portion 58 as a thinned external portion 62 including a rectangular opening 64 and a wing portion. The external portions 62 are joined by a skirt portion 66 which extends from the ring portion 58 and forms an internal shoulder 68 therewith.

The contact assembly includes the case 24, the fixed and movable contacts, the contact spring 30 and the seal element 22. The case 24 comprises a base portion 70 having an upstanding generally oval wall 72 extending therefrom around its edge to provide a contact cavity. Slots are formed in the oval wall 72 to accept the fixed terminal 26. On each side of the long portion of the external surface of the oval wall 72, a pair of posts are formed in opposed relation with each other. Each post has an extension formed therewith to provide a shoulder. The two posts provide a channel therebetween. A triangular projection 76 extends from each of the short sides of the upstanding wall 72 with its apex directed away from the plane of the base portion 70. The base of the projection 76 provides an engagement shoulder 77. A ringlike wall 78 extends upwardly from the base 70 within the area defined by the wall 72 and includes extensions which act as seats for the fixed contacts 26, 75 in the normally open design (not shown).

The seal element 22 comprises a circular seal portion 80 having an engagement portion 82 extending from each side and having a hole 84 extending centrally therethrough. A lip surrounds the hole 84 on the side opposed to that from which the engagement portions extend. The fixed terminals 26 comprise a terminal portion and a contact portion which are a continuation thereof and which have a contact 86 formed therefrom, and bent in angular relation therewith. The movable contact 28 is generally rectangular in configuration having a domed-shaped protuberance 88 and a pair of wings bent in angular relation to the remaining portion of the terminal 26.

The contact assembly is put together by placing the contact spring 30, into the cavity of the case 24 with the spring end within the ringlike wall 78. The protuberance 88 of the movable contact 28 is fitted into the other terminal end of the contact spring 30. The fixed terminals 26 are placed into the slots in the oval wall 72 with the contact 86 butted against the movable contact 28 and the terminal portion extending beyond the area of the case 24 in right angle relation to the axis thereof. The seal element 22 is engaged to the case 24 by passing the engagement portion 82 into the channel formed by the posts and by engaging the engagement portion 82 with the shoulder thereby placing the hole 84 directly over the cup of the protuberance 88.

The plunger assembly is brought together by placing the plunger spring 16 within the cavity of the inner plunger 12 and then passing the inner plunger 12, closed end first, through the hole of the outer plunger 14 until the annular flange 32 of the inner plunger 12 butts against the circumferential shoulder 34 of the outer plunger. The rod portion 40 of the divider 18 is passed into the plunger spring 16 and the flange 36 of the outer plunger 14 is passed within the wall 44 flexing it outwardly until the tongues 46 engage behind the flange 36 locking the assembly together.

We can now take the plunger assembly and pass it through the aperture 52 of the plunger holder 48 so that both the inner and outer plungers pass through the aperture and the forward edge of the divider 18 butts against the surface adjacent the aperture 52. The outer surface of the wall 44 movably engages against the arced guides of the plunger holder 48 and also against the inner surface of the legs 54. The contact assembly is passed between both the extension portions 62 until the engagement shoulder 77 of the triangle projections 76 engage within the rectangular openings 64 and the two terminal portions extend adjacent the wings of the external portions 62, completing the switch. The post portions 42 of the divider 18 are passed through the hole 84 in the seal element 22 and then into the cup formed by the protuberance 88 of the movable contact 28.

To actuate the switch, an axial force is applied on the inner plunger 12 which force is immediately transmitted to the post portion 42 of the divider 18, which in turn displaces the movable contact 28.

ble contact 28 and compresses the contact spring 30. In other words the whole plunger assembly (i.e. the inner plunger, plunger spring, outer plunger, and divider) moves as a unit initially. As the axial force continues, the inner plunger 12 is telescoped within the outer plunger 14 until the outer surface of the inner plunger 12 is on the same plane as the outer plunger 14. At this time continued force will cause the inner and outer plungers to move together into the body 20 for a predetermined distance. It may be possible for the outer plunger 14 to move first or simultaneously with the inner plunger 12. This allows us an amount of plunger overtravel, say one-half inch, after actuation of the switch, while maintaining a short switch length behind the bezel.

The purpose of the plunger assembly is to avoid the necessity of balancing the plunger and the contact spring and to eliminate any pretravel prior to actuation of the contact spring.

With reference to the foregoing description it is to be understood that what has been disclosed herein represents an embodiment of the invention and is to be construed as illustrative rather than restrictive in nature and that the invention is best described by the following claims.

We claim:

1. A switch comprising a body, a plunger assembly, and a contact assembly, the plunger assembly including a first plunger, a second plunger, a plunger spring and a divider, the first plunger telescopically engaging the second plunger, the second plunger engaged to the divider and axially movable therein and the plunger spring engaged between the first plunger and the divider, the plunger assembly movably associated with the body, the contact assembly having a fixed contact, a movable contact and the divider having means of engaging the movable contact said contact assembly engaged to the housing.
2. A switch as set forth in claim 1 wherein the contact assembly has a contact spring urging the movable contact toward the divider.
3. A switch as set forth in claim 2 wherein the force needed to deflect the contact spring is less than the force needed to deflect the plunger spring.
4. A switch as set forth in claim 3 wherein the divider comprises a base portion having a rod portion extending from one side and a post portion extending from the other side and a wall extending upwardly from the base portion in spaced circumscribed relation to the rod portion and the rod portion engaged within the plunger spring and the post portion engaging the movable contact.
5. A switch as set forth in claim 4 wherein a seal element is interposed between the plunger assembly and the contact assembly and the seal element has an aperture portion therethrough through which the post portion engages the movable contact.
